tion of Delaware

Application October 17, 1941, Serial No. 415,375

9 Claims. (CL 178—42)

The present invention relates to printing telegraph apparatus and more particularly to tape feeding mechanisms therefor.

A primary object of the present invention is to dually control the record strip feeding mechanism of a telegraph printer to permit the feeding of a record strip under different conditions of operation.

The present invention features a mechanism for feeding out a predetermined length of tape to insure the complete transmission of a perforated message.

Specifically, when the telegraph printer perforator or telegraph perforator is employed in conjunction with a transmitting distributor, provision is made to advance the tape beyond the printing and perforating points a distance sufficient to present the last transverse row of code perforations representing a character to the sensing pins of the transmitter. To achieve this result, the mechanism or arrangement according to the present invention is used. According to the specific embodiment of the present invention an auxiliary magnet is provided in the selector mechanism whereby the cam drum trip-off mechanism is operated independently of the selector magnet in the signaling line. In response to the manual operation of a contact, a circuit is closed for operating the auxiliary magnet whereupon its armature lever acts to operate the bell crank of the trip-off mechanism of the selector cam drum to initiate its rotation, and continuous rotation thereof is effectuated for the period of duration of energization of the auxiliary magnet. The period of energization of the auxiliary magnet is controlled by a worm and follower timing device.

The foregoing and other objects and features of the present invention will be better understood from the following description when taken in conjunction with the accompanying drawings, wherein

Fig. 1 is a partial plan view of the apparatus embodying the present invention;

Fig. 2 is a side elevation of the apparatus embodying the present invention;

Fig. 3 is a fragmental sectional view of the apparatus embodying the present invention;

Fig. 4 is a sectional view taken on line 4—4 of Fig. 2;

Fig. 5 is a schematic circuit arrangement in accordance with the present invention; and

Fig. 6 is a fragmental perspective view showing the dual control of the stop gate latch according to the present invention.

In Fig. 1 the present invention is indicated as being incorporated in a printing perforator mechanism such as is shown in copending application Serial No. 274,796, filed May 20, 1939, by R. A. Lake.

As mentioned in said copending application the mechanism shown is an improvement of the printing telegraph receiver disclosed in U. S. Patent No. 1,745,633, or similar printers operative to properly select the various type elements, move the tape forward, move and reverse the inking ribbon (as on a standard typewriter), and shift the platen for figure case characters, and only so much of the mechanism of said patent and copending application will be hereinafter set forth as is necessary to an understanding of the present invention. Reference may be had to said patent for a full understanding of the printer mechanism not described hereinafter in detail.

As disclosed in the above-mentioned patent and copending application, the platen 11 over which the paper tape passes from right to left is located in the front and central part of the apparatus. However, the platen used in the present invention is of different construction, comprising a cylindrical plunger carried in a rectangular block and shiftable in the manner set forth in said patent. Type bars 12 are positioned to the rear of the platen in an arcuate manner and are arranged for striking forwardly and downwardly. Just to the rear of the type bars 12 is a series of notched code bars 16 which are substantially semicircular in shape. Actuating bars 14 for operating the type bars 12 are located immediately in front of the code bars 16, and are adapted to be pulled one at a time into the alignment of notches in the code bars 16 when the notches are selectively aligned for a particular character or function. As indicated in said patent, the actuating bars 14 are articulated to the type bars 12 through a gear and rack means.

The selecting mechanism for selectively operating the code bars 16 is of the sword-and-T-type, fully disclosed in said patent. Briefly, this selector mechanism comprises a selecting or receiving electromagnet 17 (Figs. 2 and 3), the armature lever 18 of which comprises a selecting arm 19 having abutments 21 and 22 which cooperate with abutments 23 and 24 of a series of swords 25. The armature lever 18 is responsive under certain conditions of operation to the energization of the magnet 17 (for example, upon receipt of marking or current impulses) and

under other conditions to the pull of a spring 26 (for example, upon the receipt of no current or spacing impulses), the tension of spring 26 being adjustable by a screw means. The swords 25, of which there is a plurality corresponding in number to the series of code bars 16, are brought into operative engagement with the selector arm 19 by their individual operating levers 28. Swords 25 are pivotally articulated by a socket connection to their individual levers 28. Each of the levers 28 is provided with an arm 31 and is normally biased in a clockwise direction about the pivot 29 by a spring 32. Arms 31 cooperate with a series of helically arranged projections 33 on a selector cam drum 34, which is frictionally driven by a main operating shaft 35 located in a perpendicular position at the rear and to the right of the code bars 16. The main operating shaft 35 is driven continuously by a motor 36 through a pinion 37 secured to the motor shaft 38, which pinion meshes with a gear 40 operatively associated with shaft 35.

As fully described in the afore-mentioned patent, the cam drum 34 is initiated into rotation upon receipt of a starting impulse which causes the de-energization of the magnet 17, thereby releasing the armature lever 18, which then responds to the pull of spring 26 to rotate the lever 18 in a clockwise direction. Upon this movement, an eccentric screw 41 cooperates with a plunger 42 which acts in the manner shown in Fig. 5 of U. S. Patent No. 1,884,743 to release, through a lever arrangement shown in Fig. 6, a stop arm (not shown) to initiate rotation of cam 34.

The speed of rotation of selector cam drum 34 is synchronized with the speed of code impulsing so that as the armature lever 18 is operated in response to received impulses, a cam 33 acts upon its associated lever 28 to rock said lever 28 counterclockwise (as viewed in Fig. 3) to bring its sword 25 against selector arm 19. Sword 25 will be rocked clockwise or counterclockwise, depending on whether abutments 21 and 23 or 22 and 24 cooperate; for example, if abutments 21 and 23 cooperate, then the sword 25 will be swung in a counterclockwise direction and will assume the position shown in Fig. 3. On the other hand, if abutments 22 and 24 cooperate then sword 25 will be swung in a clockwise direction to assume the opposite position. After the sword 25 has been set in accordance with the nature of the signal impulse and the cam 33 passes out of operative engagement with arm 31, the lever 28 will be actuated in a clockwise direction by its spring 32, carrying its associated sword 25 along with it to impinge the sword 25 against the arms of a T-lever 45 pivoted at 46, thus rocking the T-lever 45 in a clockwise or counterclockwise direction. Each of the T-levers 45 is pivotally articulated to a code bar 16 so that when a T-lever 45 is actuated in a clockwise or counterclockwise direction, its associated code bar is set correspondingly. Accordingly, with the selecting mechanism just described, the code bars 16 are set selectively in their rightward or leftward positions (Fig. 1) in response to the impulses of a code signal.

As described in Patent No. 1,745,633, the setting of the code bars 16 is maintained during the printing operation by a detent or locking means. Accordingly, a locking bar 49 (Fig. 3) is provided which cooperates with beveled notches 51 on code bars 16. Bar 49 is pivotally mounted and is moved into and out of engagement with the code

bars 16 as the striker bar or operating bail 52 (Fig. 2) is raised and lowered. The bail 52 is operated by a cam (not shown) on the main shaft 35 in a manner described in Patent No. 1,745,633. When the bail 52 is in its lowermost position, it cooperates with the beveled edges 53 of the bars 14 and 49 to hold such bars out of engagement with the code bars 16 so that the code bars 16 may be readily shifted in accordance with the operation of the selector mechanism. When the bail 52 is operated upwardly to perform a printing operation the bars 14 and 49, due to the beveled edges 53, are permitted gradually to be actuated toward the code bars 16 by their individual springs 54. The actuating bars 14 are provided with a hook portion 55 which cooperates with the bail 52 which in its upward movement engages the hook 55 to lift the actuating bar 14, so that through the rack and pinion connection between the actuating bar and the type bar, the type bar is caused to rotate about its pivot to bring the type face downwardly to impinge upon the platen 11. The locking bar 49 is not provided with a hook portion 55, since its function is to rock on its pivot toward and away from the code bars 16 under the control of the bail 52 to lock the code bars 16 in their set position during the printing operation.

According to the present invention, the locking bar 49 while held in its position away from the code bars 16 when the bail 52 is in its lowermost position, cooperates with a series of bell cranks 56 to hold said bell cranks in their counterclockwise position. Bell cranks 56 are provided with shouldered portions 57 through the instrumentality of which rotation of the bell cranks 56 to their clockwise position is permitted or prevented by code bars 16. That is, if any of the code bars 16 is set in the position indicated in Fig. 3, and the locking bar is permitted to enter the V-notch, the bell crank 56 associated therewith is blocked through the impingement of shoulder 57 with the end of the associated code bar 16. On the other hand, if a code bar 16 assumes its opposite or rightward position as viewed in Fig. 3, the bell crank 56 associated therewith would not be blocked, but would rotate clockwise in response to spring tension and follow the movement of locking bar 49. There is provided a bell crank 56 for each of the code bars 16. Also cooperating with the bell cranks 56 is a series of levers 58, 61, and 65 which govern the positionment of a corresponding series of punch interponents 68 (Fig. 1).

Adjacent to the platen 11 is a punch block 71 carrying a plurality of punches which are controlled permutably by the interponents 68, which are slidably arranged in a cradle 69 pivoted at 72. Cradle 69 is connected by a link 73 to a perforator operating lever 74. The operating lever 74 is pivotally mounted on a pivot rod 75 supported in bearings 76 and 77. As viewed in Fig. 2, the operating lever 74 is provided with an extension 78 which cooperates with an operating cam 79 (mounted on shaft 35) through the instrumentality of a follower roller 81 carried at the end of arm 78. A spring (not shown) acts upon lever 74 to hold the cam follower roller 81 against the periphery of the cam 79.

The record material, after being perforated in the punch block 71, passes over a tape feed roller 82 which is provided with a series of spaced feed pins or projections 83 adapted to cooperate with the feed holes formed in the record strip or material by the feed punch of the punch block 71.

The feed roller 82 is provided with a series of tooth-shaped grooves 84 which cooperate with a tape feed pawl 85 pivotally carried on the cradle 69 in well-known manner. Now, upon each cycle of rotation of cam 79, the lever 14 is reciprocated so as to operate, through link 73, the cradle 69, whereupon the end of the cradle underneath the punch block 71, as viewed in Fig. 1, is raised and lowered to operate the punches through the instrumentality of the interponents 68 which have been set permutably by the code bars 16 through the instrumentality of levers 56, 58, 61 and 65. As the cradle 69 is thus operated, the pawl 85 is raised into engagement with a succeeding tooth in the feed roller 82 and thereupon, in response to the downward movement of the cradle 69, the feed roller 82 will be rotated one step, and hence through the sprocket teeth 83 the record strip inserted therein will be stepped or advanced one unit distance.

According to the principal feature of the present invention, it is the purpose of the arrangement herein disclosed to cause the tape feeding mechanism just described to be operated successively a plurality of times so as to feed out a sufficient amount of record material to insure that the last code combination perforated in the tape will be presented to the sensing pins in the tape transmitter. To this end the worm and follower timing device of the present invention is provided.

Having reference to Fig. 3, one of the cam projections 33 on the cam drum 34, as set forth in said aforementioned patent, is utilized to initiate the operation of the main operating cam sleeve 86 (Fig. 2) carried on the main shaft 35. As viewed in Fig. 3, the cam projection 33 is shown in cooperative relation with an arm 87 of a clutch throwout lever 88 pivoted on a shaft 89 journaled in brackets 91 and 92 (Fig. 2). Clutch throwout lever 88 is normally biased in a clockwise direction (viewed in Fig. 3) by a biasing spring 93. Lever 88 is provided at its lower end with an arm 94 having a laterally disposed extremity 95 which cooperates with a flange 97 on the driven portion of a clutch 96. As is well known with this type of clutch 96, the lateral portion 95 acts upon the flange 97 to cam the driven portion out of engagement with the driving portion, so that when the cam 33 acts in its rotative path to operate arm 87 of lever 88 counterclockwise against the action of spring 93, the clutch lever 88 is thus rotated to impart similar rotation to arm 94 to move the lateral portion 95 out of engagement with the stop portion on flange 97 to permit the compression spring 98 to urge the driven portion 97 into engagement or meshing relation with the driving portion of the clutch 96, thus causing the sleeve 86 to rotate. In this manner, the cam sleeve 86 is caused to rotate, and its cam 79 acts through follower roller 81 to operate perforator operating lever 78, in the manner previously described, to effect a perforating operation. Cam sleeve 86 also carries a cam 99 which cooperates with a cam follower roller 101 carried at the extremity of one arm of a lever 102 pivoted at 103 to projection 104 of a bracket 105. The opposite arm of lever 102 is provided with a downwardly projecting portion 106 on which is pivotally mounted a pawl member 107. A spring 108 is distended between a projection on pawl 107 and a projection on portion 106 to bias the pawl 107 normally in a clockwise direction (as viewed in Fig. 4) into cooperative relation with a ratchet wheel 109 integral

with a sleeve member 111 rotatably mounted on a shaft 112 journaled in brackets 113 and 114 (Fig. 2) of bracket or mounting 105. Sleeve 111 is also provided with an integral screw portion 115.

Cooperably related with the threads of the screw 115 is a follower pin 116 mounted on the extremity of a screw follower lever 117. Follower lever 117 is pivotally mounted at 118 to a portion 119 rotatably mounted on a pivot shaft 121 also journaled in the bracket member 105. Portion 119 is provided with an arm 122 which cooperates with the bent arm 123 of an armature lever 124 pivoted at 125. A spring 126 is distended between arm 123 and arm 122 so as to bias armature lever 124 and lever 119 attrahently. When the follower pin 116 is not in engagement with the screw 115, then the lever 117 is biased in its counterclockwise position (as viewed in Fig. 3) against an adjustable stop 127.

The movement or rocking of the armature lever 124 is governed by a magnet 128 and a spring 129. The spring 126 does not act to rotate the armature lever 124 but merely serves to hold arm 122 of member 119 into engagement with arm 123; that is, spring 126 governs the rotation of member 119 and its follower arm 117. When the magnet 128 is de-energized, the spring 129 acts to rotate armature lever 124 to bring its arm 131 into contact with a stop pin 132. The armature lever 124 is provided with an extension 133 which cooperates with a bank of contacts 134, comprising three contacts 135, 136, and 137.

The normal condition of the apparatus is such that when the magnet 128 is energized its armature lever 124 will act through arm 123 and arm 122 to hold the follower lever 117 in its clockwise position (as viewed in Fig. 4) to hold the follower pin 116 out of engagement with the screw 115. Then, when the magnet 128 is de-energized and its armature is released under the pull of spring 129 and caused to rotate in a clockwise direction so that spring 126 will rotate the follower lever 117 in a counterclockwise direction to bring the follower pin 116 into engagement with the screw 115, the screw 115 as it is rotated, as will presently appear, will cause pin 116 to travel along the screw 115 from right to left (as viewed in Fig. 2), until it encounters a pair of contacts 138 which are caused to be closed upon further movement of the pin 116 along said screw 115 in a leftward direction.

The tape feeding-out arrangement according to the present invention comprises also an auxiliary magnet 141 which is appropriately mounted in the selector mechanism bracket to cooperate with an armature lever 172 pivoted at 173 (Fig. 3). Lever 173 is provided with an extremity 174 (Fig. 6) which cooperates with the vertical arm 60 of a bell crank 175, in the same manner as does the plunger 42, to operate said bell crank 175 counterclockwise (as viewed in Fig. 6) to cause the stop gate latch 176 to be rocked clockwise to free the stop gate 177 for rotation in response to pressure exerted by a stop arm (not shown) carried on the cam drum 34. Thus, it is seen that when the magnet 141 becomes energized, as will presently appear from the following description of operation and of the description of the circuit shown in Fig. 5, its armature lever 172 will be rocked clockwise (as viewed in Fig. 3) to cause its end or extremity 174 (Fig. 6) to rock the bell crank lever 175 and to hold or maintain it in its 65 rocked or counterclockwise position so long as 70 75

the magnet 141 remains energized. In response to this condition the stop gate latch 176 is held disengaged and permits continuous rotation of the cam drum 34, so that upon each rotation of the cam drum 34 the cam 33 will act upon the clutch release or throwout lever 88. When the clutch throwout arm or lever 88 is thus operated for each revolution of the cam drum 34, the sleeve 86 is accordingly released for rotation and is rotated continuously as long as the magnet 141 remains energized. This causes constant oscillation or reciprocation of the lever 102 so that the pawl 107 continuously reciprocates back and forth to rotate the ratchet wheel 109, and hence turn the screw 115 continuously. Then, if the pin 116 is in engagement with the screw threads of 115, the lever 117 will be rotated clockwise (as viewed in Fig. 3) until it reaches the contact 138, whereupon said contact will be closed, the effect of which will appear hereinafter.

In the circuit shown in Fig. 5, the key designated 142 is located in the local printing apparatus, and the key designated 143 is located remotely of the printing apparatus. In the normal condition of reception of code signals the circuit is conditioned as shown in Fig. 5 with the contacts 144 and 145 (associated with keys 142 and 143, respectively) closed. In this condition a circuit is completed from negative battery through contacts 145 and 144, then through contact 136 and through the winding of magnet 128 to positive battery, thereby holding magnet 128 energized, since it has been previously energized over a circuit which will hereinafter be described. When either one of the contacts 144 or 145 is opened momentarily by its keys 142 and 143, respectively, the circuit for the magnet 128 is opened, and the magnet 128 is thus de-energized permitting its armature 124 to be pulled rightwardly as viewed in Fig. 5 to close a contact 137. Now when the key 142 or 143 has been released to close its respective contact, a circuit will be completed from negative battery through contacts 145 and 144, over armature 124 and through contact 137 (now closed), then through magnet 141 to positive battery. The magnet 141 now becomes energized and in so doing it attracts its armature lever 172 (Fig. 3) to operate, through end 174 (Fig. 6), the bell crank lever 175 and stop gate latch 176 to initiate the rotation of cam drum 34. The de-energization of magnet 128 has in the manner previously described caused the follower pin 116 to be brought into cooperative engagement with the screw 115.

The constant rotation of the cam drum 34, and of course the cam sleeve 86 has, through the cam 99 and lever 102, caused the pawl 107 to operate the ratchet wheel 109 continuously so as to impart continuous rotation to the screw 115. In this manner, the follower pin 116 travels across the length of the screw 115 toward the contact 138. As a result of the de-energization of magnet 128 the contact 135 was closed. Therefore, when the follower lever 117 has been operated to the point where it closes the contact 138, a circuit for re-energizing the magnet 128 will be completed from negative source of battery, through contact 145, over conductor 146 and through resistance 147, then through contact 138 (now closed), over conductor 148, through contact 135 (now closed), and through the winding of magnet 128 to positive source of battery. The energization of magnet 128, in this manner, attracts its armature 124 to open the contact 137 and close the contact 136, as well as open the con-

tact 135 thereof. The opening of contact 137 causes the de-energization of magnet 141 due to the breaking of its energizing circuit at contact 137. The closing of contact 136 completes a locking circuit, as previously described, for the magnet 128 from negative source of battery, through contacts 145 and 144, over armature 124, through contact 136 (now closed) and through the winding of magnet 128 to positive source of battery. The opening of contact 135 occurs after the closing of contact 136 because the contacts 136 and 135 form a make before break contact arrangement, thereby insuring the locking up of the relay magnet 128. The energization of magnet 128 causes, through its armature lever 124, the contact 138 to be opened, because the lever 117 is actuated to withdraw the pin 116 from the screw 115, thereby permitting the lever 117 to respond to its spring to be returned against the stop 127 in preparation for another timing operation.

Provision is made in the circuit arrangement shown in Fig. 5 whereby the automatic feeding out of the tape may be interrupted upon the resumption of signal reception; that is, in response to the first spacing signal received which is the start signal. With this arrangement the magnet 128 is connected electrically with a line relay 151 having a line winding 152 and a biasing winding 153. Line relay 151 also has an armature 154 which is oscillated back and forth in response to line signal impulses between marking and spacing contacts 155 and 156, respectively. Thus, after the cessation of reception of signal impulses, and during the period of spacing out of the tape upon the operation of a key 142 or 143, if a spacing signal is received by the line relay 151, its armature 154 is swung over to the spacing side to close the spacing contact 156, thereby completing a circuit for reenergizing the magnet 128 from negative source of battery through resistance 157, then over armature 154 and through contact 156 of the line relay 151, then over conductor 158, through contact 159 of a control magnet 161 (the function of which will be hereinafter described), then over armature 162 and conductor 163, through contact 135 (now closed, due to the fact that magnet 128 has been de-energized to perform the tape spacing operation), then through the winding of magnet 128 to positive battery, thus causing the re-energization of magnet 128 and the withdrawal of the tape follower pin 116 from the screw 115, permitting the return of the tape follower lever 117 to its stop position against the stop 127.

It sometimes becomes desirable to cut or switch out one or more of the printers in a connected series of printers in the signaling line from a remote station, such as a central station. In this connection, it is also desirable to keep or maintain the selector magnets or line relays at each station energized or continued in the line circuit. With the arrangement according to the present invention it is possible for a remote station to switch out a local station without disturbing the energization of the selector magnet 17 so that in the event the switched-out station has just completed a message and the tape out switch has been operated, the feeding out of the tape in response thereto will not be interrupted, so that the resumption of message reception by other stations will not interfere with the tape-out operation at the switched-out station. In Fig. 5, therefore, the magnet 161 is shown with one terminal of its winding connected by a conductor 164 to the point 165 of the armature 154 of the

line relay 151. Furthermore, the portion of the conductor between the contact 155 and the selector magnet 17 is branched by a conductor 166 to provide a short circuit for the selector magnet 17. Thus, when the key 167 at the remote station is operated, a circuit is completed for magnet 161 from negative battery, through resistance 151, through point 165 and over connector 164, through the winding of magnet 161, thence through the key contact 167 at the central station, thence over conductor 166 and through the winding of the selector magnet 17 to positive battery. This circuit holds the magnet 161 and selector magnet 17 energized. In this manner the selector magnet 17 is nonresponsive to the effect of the line signals upon the line relay 151, so that when the armature 154 vibrates in response to the marking and spacing signal impulses through the coil 152, the magnet 17 will remain energized over the previously described circuit. Moreover, since the magnet 161 is energized its armature 162 is attracted, thereby opening the contact 159. Then, if the tape-out mechanism controlled by the magnet 128 is in operation, it cannot be interrupted by the closing of contact 156 at the line relay in response to spacing signals as described hereinbefore because of the fact that the contact 159 is still open. Hence, according to the foregoing description, the tape-out mechanism at a particular station identified by the key 167 at the central station may be cut out of the line without cutting-out or breaking the signal line. The effect is then to render only a remote station printing mechanism ineffective or nonresponsive to line signals without disturbing the tape feed-out mechanism thereat.

Although a specific embodiment of the invention has been disclosed herein, it is understood that many changes may be made without departing from the spirit and scope of the invention as defined in the appended claims.

What is claimed is:

1. In combination, a selector mechanism, a recording device, primary means responsive to line signals for controlling, through said selector mechanism, the operation of said recording device, secondary means for controlling through said selector mechanism said recording device, a timing device effective under the control of a normally energized magnet for controlling, through said secondary means, the operation of said recording device for a predetermined period, means under the control of the line signals for interrupting the operation of said timing device, and means for rendering said interrupting means ineffective to interrupt said timing device.

2. In combination, a selector mechanism, a recording device, an electromagnetic device responsive to line signals for controlling, through said selector mechanism, the operation of said recording device, a second electromagnetic device for controlling through said selector mechanism said recording device, a screw and follower timing device controlled by a normally energized electromagnet for governing, through said second electromagnetic device, the operation of said recording for a predetermined period, means under the control of the line signals for interrupting the operation of said timing device, and means for rendering said interrupting means ineffective to interrupt said timing device.

3. In combination, a selector mechanism, a recording device, primary means responsive to line signals for controlling, through said selector

mechanism, the operation of said recording device, secondary means for controlling through said selector mechanism said recording device, a timing device effective under the control of a normally energized magnet for controlling, through said secondary means, the operation of said recording device for a predetermined period, means under the control of the line signals for interrupting the operation of said timing device, and means for rendering said interrupting means ineffective, said means including short circuiting means for said primary means to prevent its response to line signals.

4. In combination, a selecting means, a recording means, signal responsive means to control, through said selecting means, said recording means, auxiliary means also effective through said selecting means to control said recording means, delay mechanism effective under the control of a normally energized magnet for controlling, through said auxiliary means, the operation of said recording means for a predetermined period, means under the control of the line signals for interrupting the operation of said delay mechanism, and means for rendering said interrupting means ineffective to interrupt said timing device.

5. In a tape perforator, a perforating mechanism, tape advancing means, a selecting mechanism responsive to code signals for controlling said perforating mechanism, means for operating said tape advancing means once for each code signal applied to said selecting mechanism, signal responsive means effective through said selecting mechanism for controlling said tape advancing means, and means effective under the control of a normally energized electromagnet for controlling, through said selecting mechanism, the continuous operation of said tape advancing means for a predetermined period.

6. In a tape perforator, a perforating mechanism, tape advancing means, a selecting mechanism responsive to code signals for controlling said perforating mechanism, means for operating said tape advancing means once for each code signal applied to said selecting mechanism, signal responsive means effective through said selecting mechanism for controlling said tape advancing means, means effective under control of a normally energized electromagnet for controlling, through said selecting mechanism, the continuous operation of said tape advancing means for a predetermined period, and means under the control of the line signals for interrupting the operation of said last recited means.

7. In a tape perforator, a perforating mechanism, tape advancing means, a selecting mechanism responsive to code signals for controlling said perforating mechanism, means for operating said tape advancing means once for each code signal applied to said selecting mechanism, signal responsive means effective through said selecting mechanism for controlling said tape advancing means, timing means effective under the control of a normally energized electromagnet for controlling, through said selecting mechanism, the continuous operation of said tape advancing means for a predetermined period, means under the control of the line signals for interrupting the operation of said timing means, and means for rendering said interrupting means ineffective to interrupt said timing means.

8. In combination, a selector mechanism, a recording device, means responsive to code signals for controlling through said selector mechanism

said recording device, auxiliary means manually controlled and operable through said selector mechanism for also controlling said recording device, means responsive to said manually controlled means for timing its effective control, means under the control of code signals for interrupting the operation of said timing device, and means for rendering said interrupting means ineffective to interrupt said timing means.

9. In a telegraph system, a relay responsive to line signals, means controlled by said relay to control selective operations, an auxiliary electromagnet, an electromagnetic means also controlled by said relay to control said auxiliary

electromagnet, manually operative contact means effective initially to cause the de-energization of said electromagnetic means whereby an energizing circuit is prepared for said auxiliary electromagnet and subsequently to establish an energizing circuit for said auxiliary electromagnet, circuit means under the control of said relay for interrupting the operation of said electromagnetic means, and circuit means for rendering said circuit interrupting means ineffective by establishing a short circuit for said relay controlled means to prevent its response to line signals.
